UNITED STATES PATENT OFFICE.

URBAN C. THIES, OF DAYTON, OHIO, ASSIGNOR, BY MESNE ASSIGNMENTS, TO UNIT STEEL COMPANY, OF DAYTON, OHIO, A CORPORATION OF OHIO.

ADJUSTABLE PARTITION.

Application filed July 23, 1926. Serial No. 125,541.

This invention relates to partitions used in the building trade, and the primary object is the provision of partition extension units which may be used as an attachment means 5 for the edges of the main partition to the wall or ceiling of a building.

This invention is an improvement upon my prior application for Letters Patent entitled, "Partition units and construction", filed February 19, 1926, Serial No. 89,347, in which I have set forth the manner of construction of the partition units and the way in which they are connected to other partition units and partition panels. This invention is concerned with the manner of attaching the ends of the partitions to the wall or ceiling of a building so that the same pieces may be used to close spaces of different heights. For this purpose each of the joints 15 between the vertical stile members and the horizontal cross rails at the top of the partition is provided with a telescopic upwardly extending sheet metal extension which extends the stile members upwardly to the ceiling, and the lower end of which is received within and slidable vertically along the upper ends of the stile members of the partition proper. These stile extensions are preferably made in two pieces and the upper end 20 of each piece is provided with a pair of curl-plates. The two pieces are adapted to mate together to provide a hollow rectangular box-shaped stile extension.

The use of the extension as just mentioned 35 may be adapted to join the end of a partition to a vertical wall as well as for ceiling construction by merely extending the extension horizontally as continuation by the cross rail members.

The further object of the invention is the provision of upwardly extending cove strips or sheets which are curved upwardly and outwardly and which are attached to the upper part of the main partition at the joints 40 between the cross rails and stile members. These cove strips are made of suitable springy material such as sheet metal so that they may be extended upwardly to the ceiling to accommodate themselves to various vertical 45 distances and to conform to uneven ceiling conditions.

The use of these cove strips is also contemplated as finishing members for horizontally extending the partition and joining it to a 55 vertical wall of a building.

Other objects and advantages of my invention will be more fully set forth in the accompanying description, and claims, and in the drawings, of which:

Fig. 1 is a view showing the partition unit 60 from which the main partition proper is constructed and showing a curlplate which is adapted to be connected to a wall or ceiling of a building.

Fig. 2 is an elevation of a partition showing the use of the partition extensions both vertically and horizontally.

Fig. 3 is a horizontal section on the line 3—3 of Fig. 2.

Fig. 4 is an elevational detail showing the 70 manner of attachment of the cove strips to the telescopic extension.

Fig. 5 is a side elevation showing a detail of the partition shown in Fig. 2.

Fig. 6 is a section of the line 6—6 of Fig. 4. 75

Fig. 7 is a view of one unit of the telescopic extension.

Referring more particularly to the drawings a main partition is shown in Fig. 2 as consisting essentially of mating pairs of cross 80 rails 1; mating pairs of vertical stiles 2; and panel pieces 3, the ends of which are received between the inwardly extending flanges of the stiles and cross rails. The stiles and cross rails are each constructed of a pair of units 4 85 shown in Fig. 1, which are arranged in mating relation with the inwardly extending flanges 5 and 6 of each pair of units in abutting relation. These partition units have

been more fully set forth as to their manner 90 of use and the way in which they are constructed in my prior application for Letters Patent, Serial No. 89,347, filed February 19, 1926, entitled "Partition units and construction". The units are each provided with 95

curlplates 7 having hollow curl ends 8 each of which have a length slightly less than or equal to one-half the width of the units. Thus, these curlplates which are arranged in opposing pairs at diagonally opposite end 100 corners of the units may be attached together in a variety of ways by through pins 9 which extend through the aligned curls of joining units. The ends of the through pins are interiorly threaded to receive attaching screws 10 which extend through rectangular covering plates 11 provided at the junctions of horizontal and vertical rail members. The panel pieces 3 are provided with attaching holes 12 along 110

their edges, these holes being evenly spaced in a symmetrical manner from the corners of the panels so as to engage with the holes 13 provided in an evenly spaced manner along the flanges 5 and 6 of the various units 4. The holes 13 in the units 4 are provided in pairs, a large and a small hole being provided in each pair so that the large hole of one unit may receive the head of the screw which attaches a panel to an opposing unit, as set forth in my prior application already referred to.

It is intended that the various cross rails and vertical stile members should be made in quantities in only the few standard sizes. In order to close the space which will usually remain between the top of the main partition proper and the ceiling I provide upwardly extending hollow sheet metal extensions indicated generally at 14, each of which is made up of a pair of members 15 shown in Fig. 7. The members 15 have a pair of outwardly projecting sides 16 and 17 which space the mating member 15 the proper distance away as shown in Fig. 3, when these sides 16 and 17 of adjacent mating members are placed adjacent to one another. One end of each of the members 15 is provided with a pair of curl-plates 18 similar to the curlplates 7 riveted to the ends of the units 4. These curlplates havecurls 19 which are adapted to be aligned with and inserted between thecurls on attaching curlplates 20. See Fig. 1. The attaching curlplates 20 have two pairs of opposingcurls which are spaced the proper distance apart so that they may be aligned with the two pairs ofcurls provided on a complete stile extension as shown in Fig. 5. The attaching curlplates 20 are provided with holes 21 by which they are screwed or bolted to the ceiling or to the side wall of a building. Thecurls 22 provided on these plates extend downwardly and a through pin 9 passes through four alignedcurls of the attaching plates 20 and the extension members 15.

The stile extension 15 extends downwardly within the stile members in a telescopic manner. The adjacent sides of the extension members are neatly received within and slightly pinched by the inwardly extending flanges on the mating pair of units 4 as shown in Fig. 6. The width of the extension members is such that they are neatly received within a pair of mating units 4. These extension members extend below the joint between the vertical stile members and the horizontal cross rail members for a suitable distance so that they may be extended vertically by merely loosening the screws 10, which preferably serve to slightly pinch sides 16 and 17 of the extension members. The upper end of the main partition proper will thus be rigidly braced to the ceiling and the use of such extensible members permits the use of a partition made up of standard size units and

thus prevents and does away with the slow and expensive cutting and fitting to size while the building is under construction.

The method just set forth for attaching the upper part of a partition to a ceiling may be used to attach the side of a partition to a vertical wall of a building by merely permitting the extension 15 to project laterally and form extension of the horizontal cross rails 1 in the manner shown in Fig. 2. The horizontally extending projections or extensions are attached by curl attaching plates 20 which are screwed to the wall before the pins 9 are inserted to attach thecurls of the plate 20 to thecurls 19 on the extension members. 80

In order to close the space left open between the top of the partition and the ceiling by the use of the extension members just described I provide cove sheets preferably constructed of sheet metal, which are attached by the attaching screws 10 to the upper part of the main partition proper. These cove strips indicated at 23 have a length equal to the distance between the centers of the vertical stile members. Each lower corner of the cove strip is provided with an attaching hole so located that the lower end of the cove strip may extend over one-half of the upper cross rails. The two upper attaching screws 10 on each side of the partition will thus support one corner of the two adjacent cove strips provided on each side of the partition. The upper space between the top of the partition proper and the ceiling may be closed by these cove strips and a similar arrangement may be used for closing the space provided at the side of the partition where it is attached to a vertical wall without being in direct contact with the wall. 90

Where a vertical extension of a partition 105 meets at a corner with a horizontal extension of a partition as indicated in Fig. 2 the end cove strips extending both vertically and horizontally are so cut that they make a neat joint and these cove strips extend past the end joint of the partition for the full distance to the wall or to the ceiling. 110

The cove strips are made of suitable springy sheet metal material so that they may conform to uneven conditions of the 115 ceiling as indicated in Fig. 4. Both the lower and upper edges of each cove strip are provided with a beading 24 and if desired suitable attaching holes may be provided along the upper end of the cove strip for the 120 reception of screws 25 by which the cove strip may be fastened to the ceiling. The cove strips are provided in a few standard heights and are slightly curved so that the attaching screws 10 may hold them with their upper 125 ends in contact with the ceiling. When the ceiling is lower and closer to the top of the main partition proper the cove strips are bent outwardly and downwardly as shown at the left of Fig. 4. 130

I am aware that various modifications and changes may be made without departing from the spirit or the scope of my invention and I do not intend to be limited to the precise construction which has been chosen herein for purposes of illustration of one form of my invention.

What I claim is:—

1. In a partition, a main partition structure comprising longitudinal members and cross members detachably joined together at their ends, and a comparatively flat and wide extension projecting away from the junction of a cross member and a longitudinal member and aligned with and extending into one of said members, and means on said extension for detachably connecting it to an adjacent body.
2. In a partition, a main partition structure comprising mating pairs of longitudinal members and cross rail members detachably joined together at their ends, and a comparatively flat and wide hollow extension projecting away from the junction of a cross rail member and a longitudinal member and aligned with and extending telescopically into one of said members, and means on said extension for detachably connecting it to an adjacent wall.
3. In a sheet metal partition, in combination, a main partition structure comprising mating pairs of longitudinal members and cross rail members joined together at their ends, and a comparatively flat and wide hollow sheet metal extension projecting away from the junction of a cross rail member and a longitudinal member and aligned with and extending telescopically into one of said pairs of members, said extension being formed of interfitting sheet metal sections, and means on said extension for detachably connecting it to an adjacent part of a building.
4. In a partition, a main partition structure comprising a series of structural units arranged in mating pairs and having panels supported thereby, said units having their adjacent sides open and provided with inwardly extending flanges on said open side, and an extension having a thickness substantially equal to the distance between the said flanges and having a width fitting within a pair of units, and said extension being adapted to be telescopically engaged by a pair of said units.
5. In a wall structure of the class described, a main structure comprising a series of sheet metal structural units arranged in mating pairs and having panels supported thereby, said units having their adjacent sides open and being provided with inwardly extending flanges on said open sides, and an extension having a thickness substantially equal to the distance between the said flanges and having a width fitting within a pair of units, said extension consisting of a pair of flanged sheet

metal plates with the flanges of the plates adjacent and serving to space said plates, and extensions at an end of each of said plates adapted to be detachably connected to other similar extensions of an attaching member.

6. In a wall structure of the class described, a main structure comprising a series of sheet metal structural units arranged in mating pairs and having panels supported thereby, said units having their adjacent sides open and being provided with inwardly extending flanges on said open sides, and an extension having a thickness substantially equal to the distance between the said flanges and having a width fitting within a pair of units, said extension being telescopically engaged by a pair of said units and consisting of a pair of flanged sheet metal plates with the flanges serving to space said plates apart, and a pair of curl plates provided at one end of each of said flanged plates to provide a pair of aligned hollow curls adapted to be detachably connected and aligned with curls of an attaching member.

7. In a sheet metal partition, a main partition structure comprising mating pairs of upright members and cross rail members having elongated hollow connection means at their ends, and means for detachably connecting said connection means together, and a flat and wide hollow sheet metal extension projecting upwardly from a junction of a cross rail and a vertical member and telescopically received by said vertical member, said extension having a thickness substantially equal to the distance between the connection means at the ends of the said members, and means on said extension for detachably connecting it to an adjacent part of a building.

8. In a partition as set forth in claim 1, a cove strip attached to said main partition structure and extending away from said main partition structure to an adjacent surface.

9. In a partition as set forth in claim 1, a curved cove strip extending away from said partition, and means for detachably connecting and supporting said cove strip at the corners of one side thereof to the said members.

10. In a partition, in combination, a main partition structure, an extensible series of braces telescopically received by said main structure and extending away from said structure to the ceiling, means for detachably connecting said braces to the ceiling, and a series of cove sheets extending outwardly and upwardly from the said structure and adapted to assume various positions dependent upon the distance between the ceiling and the said structure, and means detachably connecting said cove sheets at their lower corners to the said structure.

11. In a partition, a main structure, an extensible series of braces telescopically received in said main structure extending away from said structure to an adjacent part of a build-

- ing, and a curved cove strip having considerable flexibility so as to assume various positions dependent upon the distance to said adjacent part of the building supported from 5 said main structure and extending away from said structure in smooth continuation of a side thereof to the said part of the building.
12. A sheet metal structural unit extension of the class described, comprising a hollow 10 sheet metal part having means at one end for detachably fastening it in place, said part being adapted to be telescopically engaged at its other end by another structural member.
13. A sheet metal structural unit extension 15 of the class described, comprising a hollow flat and wide sheet metal part, and curl shaped extensions at one end of said part for detachably fastening it in place, the other end of said part having a uniform substantially rect- 20 angular section so that it may be telescopically engaged by another structural member.
14. A sheet metal structural unit extension 25 of the class described comprising a hollow sheet metal part constructed of a pair of flanged plates, the flanges in said plates serving to space the plates apart, means at one end of each of said plates for detachably fastening the said plates in place, said plates being 30 adapted to be telescopically engaged at one end by another structural member.
15. A sheet metal structural unit extension 35 of the class described, comprising a hollow sheet metal part constructed of a pair of flanged plates, the flanges in said plates serving to space the plates apart, means at one end of each of said plates for detachably fastening the said plates in place, said plates being

adapted to be telescopically engaged at one end by another structural member, said means comprising hollow elongated tubular projec- 40 tions arranged in opposing pairs.

16. A cove strip for finishing a partition end, comprising a sheet of metal having considerable flexibility and bent into curved form, and having a free side adapted to assume various positions in relation to the supported side, said sheet being provided with an attaching hole at opposite corners of one side by which it may be attached firmly in place to the partition. 45

17. A curved ceiling cove strip for finishing the upper end of a partition, comprising a rectangular sheet of metal having considerable flexibility and having a free side curving outwardly and upwardly to a terminal edge and adapted to assume various positions in relation to the supported side, said supported side having an attaching hole at each corner by which it may be firmly attached to the partition. 55

18. A ceiling cove strip for finishing a partition end, comprising a rectangular sheet of metal having a pair of opposite beaded sides, one of which is adapted to contact with the ceiling in various relations dependent upon the distance from the ceiling to the other side of said cove strip, said strip having means at each corner adjacent the other side by which it may be supported at its lower beaded side from the partition. 65

In testimony whereof I have hereunto set my hand this 27th day of July, 1926.

URBAN C. THIES.
